[57] CLAIM

The ornamental design for a self-inking hand stamp, as shown and described.

DESCRIPTION

FIG. 1 is a top, left front perspective view of a self-inking hand stamp showing our new design;

FIG. 2 is a front elevational view;

FIG. 3 is a left side elevational view, the right side being a mirror image thereof;

FIG. 4 is a rear elevational view;

FIG. 5 is a top plan view; and

FIG. 6 is a bottom plan view thereof.

Fig. 1.

Fig. 2.

Fig. 3.
